(57) **CLAIM**

The ornamental design for a vertical trifold cell phone wallet,
as shown and described.

DESCRIPTION

FIG. 1 is a perspective view of a vertical trifold cell phone
wallet with interior slot pockets according to one embodiment
showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the vertical trifold cell phone
wallet with interior slot pockets in an open condition;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a perspective view of the vertical trifold cell phone
wallet with interior slot pockets in a stand configuration;

FIG. 16 is a front view thereof;

FIG. 17 is a rear view thereof;

FIG. 18 is a left side view thereof;

FIG. 19 is a right side view thereof;

FIG. 20 is a top view thereof;

FIG. 21 is a bottom view thereof;

FIG. 22 is a perspective view of a vertical trifold cell phone
wallet with an exterior slot pocket and interior slot pockets
according to another embodiment showing my new design;

FIG. 23 is front view thereof;

FIG. 24 is a perspective view of the vertical trifold cell phone
wallet with an exterior slot pocket and interior slot pockets in
an open condition;

FIG. 25 is a front view thereof;

FIG. 26 is a rear view thereof;

FIG. 27 is a front view thereof; and,

FIG. 28 is a bottom view thereof.

The broken lines showing portions of a wallet are for the
purposes of illustrating environment and form no part of the
claimed design.

1 Claim, 22 Drawing Sheets
